PISTON CONSTRUCTION

Frank C. Druzynski, Bloomfield Hills, Mich., assignor to Continental Aviation and Engineering Corporation, Detroit, Mich., a corporation of Virginia

Filed Nov. 21, 1963, Ser. No. 325,272

4 Claims. (Cl. 123—41.35)

The present invention relates to internal combustion engines and more particularly to pistons for such engines having means for cooling the piston in the vicinity of the piston ring grooves.

The present invention is especially applicable to those internal combustion engines in which the combustion chamber is arranged entirely or substantially within the face of the piston although as the description proceeds it will be apparent that the present invention will be suitable for other types of pistons as well.

The advantages of providing the combustion chamber within the face of the piston have been known for some time. The most desirable shape for such a chamber has been found to be a nearly hemispherical hollow space or cavity extending well into the face of the piston.

One of the problems encountered in such pistons is that the relatively thin wall which separates the combustion chamber from the ring groove area readily transmits heat produced in the chamber to the area of the ring grooves. High temperatures especially in the area of the top ring groove tends to produce fuel deposits which will eventually cause the piston rings to score the walls of the cylinders.

A copending application, Serial No. 325,271, filed November 21, 1963, by Walter F. Isley, discloses and claims pistons provided with means for cooling the ring groove area of the piston head. The present invention provides an alternate method of constructing such pistons.

It is an object then of the present invention to reduce fuel deposits in the vicinity of the top ring groove of pistons for internal combustion engines by providing means for cooling this area of the piston during operation of the engine.

It is another object of the present invention to increase the efficiency of internal combustion engines by providing a cavity in the piston head for such engines positioned closely adjacent the top ring groove thereof and means for circulating oil through the cavity.

It is still another object of the present invention to simplify the manufacture of pistons having an annular cooling cavity provided in the head thereof by providing a ring member adapted to seat in the cavity and providing support for a weld to close the cavity.

Still further objects and advantages of the present invention will be readily apparent to one skilled in the art to which the invention pertains upon reference to the following drawings in which like reference characters refer to like parts throughout the several views and in which

FIG. 1 is an elevational top view of a piston of the present invention.

FIG. 2 is a cross sectional view taken substantially at line 2—2 of FIG. 1.

FIG. 3 is a fragmentary cross sectional view taken substantially on line 3—3 of FIG. 1 with portions shown schematically for purposes of clarity, and

FIG. 4 is an enlarged cross sectional view of a ring member of the present invention.

Description

Now referring to the drawings for a more detailed description of the present invention a preferred piston 10 is illustrated as having a head portion 12 and a skirt 14.

2

The head portion 12 is provided with a planar face 16. A substantially spherical combustion chamber cavity 18 is provided in the face 16 and extends well into the head portion 12 as shown. A groove 20 is formed in the face 16 as can best be seen in FIG. 1 to direct fuel from an injection nozzle (not shown) into the combustion chamber cavity 18.

The substantially annular exterior surface 22 of the head portion 12 is provided with a plurality of axially spaced ring grooves 24 and a top ring groove 24A. Each of the grooves 24 and 24A is adapted to carry a conventional piston ring (not shown).

The face 16 is provided with an axially extending annular recess indicated generally at 26. The recess 26 comprises an upper portion preferably formed by angularly inwardly extending walls 28, a radially elongated medial portion 30 and an axially extending elongated lower portion 32. An annular shoulder 34 is formed intermediate the medial portion 30 and the lower portion 32.

A ring member 36 as can best be seen in FIG. 4 preferably comprises an axially extending flange portion 38 and a radially extending flange portion 40. The ring member 36 is adapted to be inserted in the recess 26 and the axially extending flange portion 38 is provided with an annular seat portion 40 complementary to and adapted to engage with the shoulder 34. The radially extending flange portion 40 extends across the recess 26 and is adapted to be wedged into position engaging a corner portion 39 formed in one of the walls 28. With the ring member 36 in the position described a suitable welding material 42 is used to fill the recess 26 above the ring member 36. In this way an annular cavity 44 is provided in the head portion 12 in a position intermediate the combustion chamber cavity 18 and the area of the ring grooves 24—24A. The cavity 44 extends at least below the plane of the top ring groove 24A.

The skirt 14 is preferably hollow as shown to provide a substantially annular recess 46. Wrist pin bosses 48 extend radially inwardly from opposite sides of the recess 46 and are provided with axially aligned openings 50. The openings 50 are adapted to receive a wrist pin (not shown).

As can best be seen in FIGS. 1 and 3 a conical inlet 52 is provided in the head portion 12 intermediate the recess 46 and the cavity 44. The inlet preferably has the larger cross sectional portion thereof in registry with the recess 46 and opens high in the cavity 44. An outlet 54 is also provided in the head portion in a position spaced from and substantially opposite the inlet 52. The outlet 54 provides communication between the lower portion of the cavity 44 and the recess 46. A nozzle 56 directs a stream of oil delivered by the oil pump 58 into the conical inlet 52.

In operation oil is delivered from the oil pumping system of the engine and by the nozzle 56 through the inlet 52 and into the cavity 44. The conical shape of the inlet 52 insures that the major portion of the oil will reach the cavity 44 regardless of the axial position of the piston 10. The inlet 52 being positioned high in the cavity 44, prevents the oil from escaping through the inlet 52 and the reciprocating movement of the piston 10 during operation of the engine will result in the oil being moved annularly through the cavity 44 and out the outlet 54. This provides a substantial cooling of the piston especially in the area of the top ring groove 24A. By reducing temperatures in this area, ring groove deposits are substantially eliminated since a temperature is maintained below the coking temperature of the fuel being used to operate the engine.

In the particular embodiment disclosed, it has been preferred to construct the ring member 36 of copper although it is apparent that other materials can be used.

The piston herein disclosed provides a simple construction for providing a cavity in the head of a piston and one which produces a relatively economically produced piston having such a cavity.

Although I have described a single embodiment of the present invention, it is apparent that many changes and modifications can be made without departing from the spirit of the invention as expressed by appended claims.

I claim:

1. In an internal combustion engine a piston assembly 10 comprising
  - (a) a piston member having a head portion,
  - (b) said head portion being provided with a top planar surface and an annular surface extending on an axis substantially normal with respect to said top surface,
  - (c) a combustion chamber cavity extending into said head portion from said top surface,
  - (d) an annular cavity being provided in said head portion intermediate said combustion chamber cavity 20 and said annular surface,
  - (e) an annular recess being provided in said top surface in registry with said annular cavity,
  - (f) said cavity being provided with an enlarged portion to form a radially extending shoulder portion 25 and a corner portion spaced radially inwardly from said shoulder portion,
  - (g) a ring member having a portion seated on said shoulder portion and a radially extending flange portion adapted to be wedged against said corner portion, and
  - (h) said recess above said ring member being filled with a welding material whereby to close said cavity.

2. The assembly as defined in claim 1 and including means circulating a coolant through said annular cavity.

3. The assembly as defined in claim 1 and in which (a) said annular surface is provided with a plurality of axially spaced piston ring grooves,

(b) said annular cavity being positioned closely adjacent said piston ring grooves, and

(c) means circulating a coolant through said annular cavity whereby to cool the area of said head portion having said piston ring grooves.

4. The assembly as defined in claim 3 and in which said circulating means comprises,

(a) an inlet provided in said head portion and registering with said annular cavity,

(b) an outlet provided in said head portion substantially radially opposite said inlet, and

(c) means adapted for connection with the oil supply system of said engine and operable to deliver a stream of oil to said inlet.
